CLAIM

The ornamental design for a multimodal fitness bar as shown and described.

DESCRIPTION

FIG. 1 is a top, front, right-side perspective view of the multimodal fitness bar.

FIG. 2 is a front view thereof.

FIG. 3 is a rear view thereof.

FIG. 4 is a right-side view thereof.

FIG. 5 is a left-side view thereof.

FIG. 6 is a top view thereof; and,

FIG. 7 is a bottom view thereof.

The broken lines in all the figures are included for the purpose of illustrating portions of the multimodal fitness bar that form no part of the claimed design.

1 Claim, 5 Drawing Sheets
